Primary Examiner — Robin V Webster**CLAIM**

The ornamental design for a toilet rim block holder, as shown and described.

DESCRIPTION

FIG. 1 is a top, front, right perspective view of a toilet rim block holder showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing the remainder of the toilet rim block holder are for environmental purposes only and form no part of the claimed design.
